DOOR SLAM MUFFLER

Ben L. Fry, St. Louis, Mo., assignor to Itsa Mfg.
Co., St. Louis, Mo., a corporation of Missouri

Application June 24, 1947, Serial No. 756,673

1 Claim. (Cl. 16—86)

1

My invention relates to buffers broadly, but more particularly to such devices that are intended to be affixed to doors and the like so as to muffle the noise of slamming, caused by the door striking against the jamb with which it cooperates.

This invention has among its objects the production of such a device that will be extremely simple to make and apply, relatively low in cost, of few parts, long-lasting, neat and attractive in appearance, and which will be otherwise efficient and satisfactory for use for the purposes intended.

One of the principal objects of my invention is to so construct a door slam muffler of the kind described, that it will include a sponge-rubber cushion insert as the element to absorb the shock of impact with the door in the closing movement of the latter, and which will be compressed thereby for substantially the complete depth or thickness of said cushion.

Another object of my invention is to provide a retainer or holder for said compressibly resilient cushion, for mounting at some point on the door jamb so as to insure that the door will strike against said cushion in closing, said holder permitting said cushion to be compressed throughout the entire body thereof.

A further object of my invention is to so construct the holder or retainer of said cushion, in the form of a channel element, wherein said cushion will be received snugly between the side flanges of said element but will at the same time be a guide to permit the cushion to be compressed toward the bottom or seat of said channel and guide said cushion as the latter resiliently expands or retracts to normal position from its compressed form, the flanges of said guide element permitting the required freedom of bodily movement of said cushion in so doing.

An added object of my invention is to provide a cushion holder of the kind described, for mounting the muffler to engageably cooperate with the door and whereby a predetermined thickness of cushion projects beyond said holder, so that the free edges of said holder will act as an abutment to engage the door to limit further compression of the cushion.

A still further object of my invention is to so construct a device of the kind described, that the rubber cushion will project for only a minor portion of its depth beyond the free edges of said holder, so as to constantly insure a true path of movement of the cushion toward its seat in said holder, on compression, and minimizing

2

the possibility of transverse spreading of the cushion in compression.

Many other objects and advantages of the construction herein shown and described, and the uses mentioned, will be obvious to those skilled in the art to which the invention appertains, as will be more clearly pointed out in the claim hereunto appended.

To this end, my invention consists in the novel construction, arrangement and combination of parts herein shown and described, and as will be more clearly pointed out hereinafter.

In the drawings, wherein like reference characters represent like or corresponding parts throughout the views,

Figure 1 is a perspective view of a portion of a swinging door and of the jamb that cooperates therewith, showing one of my devices mounted in place thereon;

Figure 2 is a transverse cross-sectional detail, showing the door in its closed position against the jamb; and

Figure 3 is a perspective view of one of such muffler devices ready for mounting in place.

Referring more particularly to the drawings, wherein I have illustrated a preferred embodiment of my invention, there is shown a portion of a door 1, of any size, shape and construction, although the one shown is a screen door. As usual, such a door may seat or close against a jamb 2 of the enclosing framework, and only that edge of the door that swings open and closes is illustrated, for the sake of convenience and clarity.

When such doors are closed forcibly, either by hand or by means of some sort of a spring or other mechanical closer, not shown, there is usually sufficient noise arising therefrom to cause irritation and annoyance to those close by, and mufflers, buffers or the like have been interposed between the elements that forcibly engage one another, and my improved form of such a device will now be set forth.

An elongated holder, retainer or guide element in the form of a channel-member with a pair of spaced apart side flanges 3—3 connected by a bottom wall 4 is made of sheet metal or some other suitably stiff and sturdy material, preferably non-rusting, as of aluminum or the like.

Apertures 5 are formed through the pair of opposed flanges to receive the fastening screws 6 whereby the holder may be affixed at the desired location, along the jamb 2. One or more of such holders may be used, as the need arises. In mounting the holders, care should be taken that

the free edges of said flanges thereof terminate approximately flush with the striking face of the jamb, so as to insure proper closing of the door.

An elongated strip of some highly compressible, resilient material, such as sponge rubber or the like, 7, of a length corresponding to that of the holder, is seated in each such holder, the width of said cushion insert 7 being approximately equal to the spacing apart of said pair of flanges 3-3, so that said insert is compressible for substantially its full depth and length into the holder, with the side flanges snugly engaging the side walls of said insert and acting as guides in the compression of the cushion by the door in closing and as is illustrated in Fig. 2, wherein the dotted line indicates the extended position of the cushion, while the full lines indicate its compressed position.

It may be mentioned here and is important, that the thickness or depth of the cushion is so proportioned that when it is placed within the channel-shaped retainer, and seats against the bottom of the latter, the major portion of the depth of the cushion is within said retainer, while only a minor portion of its height projects outwardly beyond or above the free edges of said flanges.

Openings 8 may be provided through said cushions so as to permit said screws 6 to pass through said flanges and screw into the material of the jamb itself.

As previously mentioned, the holders are affixed to the jamb so that the terminal edges of the flanges are approximately flush with the door-striking face of the jamb, whereby there is a predetermined height of cushion projecting therebeyond, in the direction to receive the striking face of the door.

Now, when the door moves to closed position, its free edge strikes against the projecting face of the cushion and compresses the latter throughout its body, except immediately between the screws and the bottom of the channel element, but as this portion of the cushion is so extremely small in proportion to the body of the whole cushion, it can be said with fair accuracy, that the whole body of cushion is compressed. The cushion is pressed toward the bottom of the channel element, to firmly seat thereagainst, and substantially the whole body of cushion is compacted toward said seat with the exception of those zones of the cushion between the screws and the bottom wall 4 of the channel.

Hence, it is seen that said element forming the holder, does not interfere with the compression or expansion of the cushion, either in compression or in retraction to projected position, and therefore the holder is a true guiding element and there is little or no tendency of transverse spreading of the cushion in its movement.

With such manner of substantially free com-

pressibility of the cushion, only the minor portion need be extended beyond the flange edges, and such a cushion will last for an unusually long time without requiring replacement.

The extent of compression of the cushion is limited by said pair of flanges, because when the door strikes against the free edges of said flanges, the latter act as a stop or abutment for further compression of the cushion.

Having thus described my invention, it is obvious that various immaterial modifications may be made in the same without departing from the spirit of my invention; hence I do not wish to be understood as limiting myself to the exact form, arrangement, construction and combination, or uses herein shown and described, except as limited by the state of the art to which this invention appertains, and by the claim hereunto appended.

What I claim as new and desire to secure by Letters Patent is:

20 A buffer for placement between a door and its jamb, said jamb having a door engaging surface, said buffer comprising an elongated channel element having spaced elongated flanges and adapted to be applied to said jamb so that the free edges of its spaced flanges oppose the door and are in the plane of the door engaging surface of the jamb, a cushion formed of highly compressible material and held between said spaced flanges in snug engagement therewith to guide said cushion during compression into said channel, said flanges being co-extensive with the major portion of the width and length of said cushion whereby the outer edge of said cushion will project a predetermined distance beyond the free edges of the flanges and the door engaging surface of the jamb, and securing screws extending transversely through said flanges and cushion adjacent the bottom of the channel, said cushion being engageable by closure of the door to produce a compression of said cushion throughout the full depth thereof with the exception of the zones of the cushion between the screws and the bottom of the channel and thereby force the outer edge thereof into the space between said channel flanges, whereby further movement of the door will be limited by engagement with the free edges of said channel flanges and the door engaging surface of the jamb.
